UNITED STATES PATENT OFFICE.

GEORGE C. JOHNSTON, OF PITTSBURGH, PENNSYLVANIA, AND LESLIE S. UPHOFF, OF SCHENECTADY, NEW YORK.

GUARD FOR X-RAY TUBES.

1,400,607.

Specification of Letters Patent. Patented Dec. 20, 1921.

Application filed August 21, 1919. Serial No. 319,036.

(FILED UNDER THE ACT OF MARCH 3, 1883, 22 STAT. L. 625.)

To all whom it may concern:

Be it known that we, GEORGE C. JOHNSTON and LESLIE S. UPHOFF, citizens of the United States, and residents of Pittsburgh, Pa., and Schenectady, N. Y., respectively, 5 stationed at Washington, D. C., have invented an Improvement in Guards for X-Ray Tubes, of which the following is a specification.

10 The invention described herein may be used by the Government, or any of its officers or employees in prosecution of work for the Government, or by any other person in the United States, without payment of any 15 royalty thereon.

This invention relates to X-ray machines and, particularly, to means for protecting the terminals of the X-ray tube, so that neither the patient nor anyone else near the 20 tube can be accidentally electrically shocked.

The terminals of an X-ray tube carry high tension current while the machine is in operation, and many accidents occur with the usual construction of exposed or unguarded 25 terminals, by persons being shocked thereby.

The basic object therefore, of our invention is to provide grounded metallic protecting means for the terminals of an X-ray tube.

30 A further object is to provide protecting means which will not cease to function unless entirely removed from the tube stand.

A further object is to provide a structure which will not be unsightly or cumbersome, 35 and which will not add appreciably to the space occupied by the X-ray tube-stand.

A further object is to construct the guards so that they will serve the additional function of supports of the X-ray tube, thus doing away with the tube supports ordinarily 40 used on the tube stand.

A further object is to provide, in combination with a guard of the character described, a yieldingly and resiliently support- 45 ed socket for the X-ray tube, thus obviating the tendency of the screw base of the X-ray

tube being broken off in the operation of screwing the same in its socket, which is likely to happen with a rigidly supported 50 socket.

Incidentally, the guards serve to cut off some of the stray radiation which emanates from the side openings in the lead glass

bowl, thus protecting the patient from detrimental or injurious effects.

With these objects in view, the invention resides in grounded metallic protecting means for the tube-terminals, whereby the grounded metallic protecting means is always between the dangerous tube-terminals 60 and any person near the tube ends, thus affording absolute protection.

The invention resides, further, in interposing between the terminals and the grounded metallic protectors sufficient insulation, so that the device may be made small enough to be practical and convenient. If only air were used for insulation, the large size necessary would make the device extremely bulky and unwieldy.

70 The accompanying drawings clearly disclose an exemplary construction capable of carrying out the underlying principles of the invention. Like reference characters designate corresponding parts in all the 75 views. Briefly described:—

Figure 1 is a view in side elevation of an X-ray tube-stand equipped with our improvements;

Fig. 2 is a view in end elevation of one 80 of the guards, looking at the open end thereof;

Fig. 3 is a fragmentary central vertical sectional view of the protecting tubes carried by the cathode guard;

Fig. 4 is a collective view of the two guards, one for the cathode end of the X-ray tube and the other for the anode end thereof; and

Fig. 5 is a detail view in end elevation, 90 looking at the open end of one of the tubular guards, showing more particularly the means for yieldingly supporting one end of the X-ray tube; and

Fig. 6 is an enlarged sectional view taken 95 on the line 6—6, Fig. 4.

Referring, now, in detail to the drawings:—

The two guards are alike in the following respects, namely, both have a metallic body 100 1, a cylinder 2 of insulating material, with a screw-plug 3 of insulating material screwed into one end thereof, a bar or plate 4 of insulating material vertically disposed at the end of the cylinder 2 opposite the 105 plug end thereof, and a clip 5, all of which

parts will be more particularly described hereinafter. While we have shown the cylinder 2 and the plug 3 as two pieces, it will be understood that the tube may be made with an integral closed end, as by molding.

The metal body 1 is a shell comprising, preferably, a base or floor 6, the side walls 7, 7, and the end wall 8. The side walls 7, 7, at one end, are upwardly extended, as shown at 9. The extensions 9 are connected by a vertically disposed plate 10 spaced from, and parallel with, the end wall 8 and having a curvilinear edge forming a cradle for the cylinder 2, thereby supporting the latter toward one end thereof. The other end of the cylinder 2 is supported by a vertically disposed insulating piece 4, which may be secured to the cylinder 2 and metallic body 1 in any suitable manner, as by screws 11. The insulating piece 4, at its bottom, is cut away centrally, as shown at 12.

A metallic clip 13 connects the metal body 1 with the metal parts of the tube-stand 14. The clip contacts with the floor 6 of the metal body 1 at the open end thereof, and with a metal part of the tube-stand 14. The clip may be attached to the tube-stand by screws 15. The metal body 1, thus electrically grounded through the tube-stand 14, is always between the dangerous tube-terminals and any person near the tube-ends, and thus affords absolute protection. It should be noted that even if the insulation 2 breaks down, the protective value of the guards is not impaired. Also, if the tube-stand is not deliberately grounded by a wire, or if this wire accidentally comes off, the tube-stand is always as well grounded by means of the floor as is any person near it, and there would, therefore, be no difference in potential between the person and the metal guards.

One of the cylinders 2 (which may be termed the cathode cylinder) carries internally a screw socket 16, into which an X-ray tube 17, provided with the usual screw base, may be screwed. The socket 16 is carried by a member 18, which, in turn, is supported from the plug 3 by a leaf-spring 19. The socket 16 is thus yieldingly and resiliently supported. It will thus be seen that, in screwing an X-ray tube into said socket, the danger of breaking the screw base from the tube (which would be apt to occur if the socket were rigidly supported) is obviated.

Carried by the member 18 and projecting axially into the socket 16 is a sliding pin 20 projected into the socket 16 by a spring 21 bearing against the head of the pin and disposed in a recess in said member 18, as shown in Fig. 4. By the construction described, it will be noted that an X-ray tube screwed into the socket 16 may be turned one and one-quarter turns after it contacts 65 with the pin 20, thus enabling the focal

spot of the target to be pointed in any direction.

Two electrical wires 22, 22 are connected to the electrical terminals of the socket 16, as shown in Fig. 4, and extend up through 70 the insulating and protecting tube 23 to the insulating plug 24 carrying the hollow metal rods 25, 25, (see Fig. 3) into which the upper ends of the wires 22, 22 project. A removable connector 26 seats on top of 75 the plug 24.

The tube 23 carries toward its upper end a hook 27, which serves a dual function, viz., it retains in position the plug 24 and also prevents the connector 26 being pulled off 80 by upward stress on the wire 28, which passes over an overhead pulley and is always taut. It will be understood that, as usual, that portion of the tube-stand carrying the tube is tiltable.

Suitable means are provided to the open end of one of the cylinders 2 for holding the X-ray tube from turning. In this instance, such means comprises two curvilinear arms 29, 29 pivoted at their lower ends, as at 30, 90 30, to the cylinder 2, at the open end thereof, and spring-pressed toward each other by a spring 31 secured to and connecting said arms at the top thereof.

The arms 29, 29 are provided, intermediate their length, with rubber inserts 32, 32, constituting cushioning elements, which bear against the X-ray tube 17 in use.

Disposed internally of the anode guard 2 is a resilient clamp, comprising a plurality 100 of spring metal fingers 33. In this instance, this spring clamp is preferably an integral member stamped out of a blank of sheet metal and bent up to shape. The spring metal clamp is secured as by screws 34, to a 105 metal bar or rod 35 inclosed by an insulating tube 36. The rod or bar 35 may be secured against longitudinal movement by any suitable means, in this instance by a screw 37 carried by the tube 36. At its upper end, 110 the rod 35 is provided with a perforation 38, so that the corresponding end of the wire 28 may be secured thereto.

Having described our invention, what we claim as new and desire to secure by Letters Patent, is:—

1. The combination, with an X-ray tube-stand, provided with the usual X-ray tube, of grounded metallic guards for said tube, carrying a pair of insulating members enclosing said tube.

2. The combination, with an X-ray tube-stand, provided with the usual X-ray tube, of grounded metallic guards for said tube, carrying a pair of insulating cylinders in 125 which said X-ray tube is disposed.

3. The combination, with an X-ray tube-stand, provided with the usual X-ray tube, of grounded metallic guards for said tube, carrying insulating cylinders in which said 130

- tube is disposed, and insulating plugs closing one end of said tubes.
4. In an X-ray tube-stand, provided with the usual X-ray tube, an insulating cylinder, in which said tube is disposed, a tube-holder disposed in said cylinder, and a sliding contact pin projecting axially into said tube holder.
5. In an X-ray tube-stand, provided with the usual X-ray tube, an insulating cylinder in which said tube is disposed, a tube-holder disposed in said cylinder, and a spring-pressed pin projecting axially into said tube holder.
- 10 6. In an X-ray tube-stand, provided with the usual X-ray tube, an insulating hollow
- member in which said tube is disposed, and means for yieldingly supporting one end of said tube, comprising a pair of arms pivoted at one end thereof to said member and 20 spring pressed toward each other.
7. In an X-ray tube stand, provided with the usual X-ray tube, a pair of insulating hollow members in which the respective ends of the tube are disposed, a resiliently supported tube socket mounted in one of said members, a pair of tube engaging arms pivoted to the other of said members and a resilient clamp disposed within said latter member.
